UNITED STATES PATENT OFFICE.

RAYMOND C. COBURN, OF UPPER SANDUSKY, OHIO.

APPARATUS FOR ADMINISTERING ANESTHETICS.

SPECIFICATION forming part of Letters Patent No. 782,108, dated February 7, 1905.

Application filed November 18, 1903. Serial No. 181,648.

To all whom it may concern:

Be it known that I, RAYMOND C. COBURN, a citizen of the United States, residing at Upper Sandusky, in the county of Wyandot and State of Ohio, have invented a new and useful Apparatus for Administering Anesthetics, of which the following is a specification.

This invention relates to a novel apparatus for use in administering anesthetics, particularly a mixture of nitrous oxid and oxygen.

The primary object of the invention is to produce an extremely simple and compact arrangement of parts, enabling the entire apparatus to be either packed in a small case for transportation and organized for instant use or packed in still smaller compass with the parts disassociated, as desired.

A further object of the invention is to equip the apparatus with gas-bags and with means whereby each of said bags may be supplied with nitrous oxid or oxygen, as the case may be, from a plurality of cylinders or reservoirs, so that upon the depletion of the gas in either cylinder the gas will be supplied from another cylinder without the loss of time or the necessity for putting a new cylinder in place.

A further object of the invention is to provide means engaging the opposite ends of the cylinders to avoid the possibility of displacement when the apparatus organized for use is carried from one point to another.

Further objects of the invention subordinate to those enumerated will appear during the succeeding description of the preferred construction illustrated in the accompanying drawings and succinctly defined in the appended claims.

In the said drawings, Figure 1 is a perspective view of the apparatus equipped for use, the tube leading to the inhaler being broken away. Fig. 2 is a top plan view of the same subject-matter with the bags and cylinders removed. Fig. 3 is a vertical section of the apparatus with the gas bags and cylinders removed and showing some of the parts in elevation. Fig. 4 is a detail view of the cylinder-retaining bracket. Fig. 5 is a detail plan view, partly in section, showing the arrangement of the cylinder-necks within a pair of

yokes and the manner in which said necks are placed in communication with a bag-nipple.

Like numerals of reference designate corresponding parts in the several figures of the drawings.

The entire apparatus is supported by a base-plate 1, upon which is screwed an internally-threaded socket 2 for the reception of the lower threaded end of a detachable standard 3. The stem or standard 3 comprises separable upper and lower sections 4 and 5, having their contiguous ends oppositely threaded for engagement with a coupling 6, by means of which the sections are secured rigidly in axial alinement. The upper section 4 of the standard has its upper end threaded for a considerable distance and is screwed into the lower side of a three-way fitting 7, from which extends in opposite directions a pair of pipes 8 and 9, connected by elbows or angle fittings 10 and 11 to depending nipples 12 and 13, to which latter gas-bags 14 and 15 are designed to be attached permanently in any desired manner. It may be noted at this point, however, that the gas-bags hang vertically and are of proper size to be supported above the base 1.

From one side of the three-way fitting 7 is extended a horizontal nipple 16 for the attachment of the inhaler-tube 17, designed to convey the gas from the bags 14 and 15 to the inhaler. (Not shown.) The flow of the gas from the bags is regulated by controlling-valves 18 and 19, located in the pipes 8 and 9, preferably adjacent to the fitting 7, and operated by comparatively small hand-wheels 20 and 21, the upper edges of which do not project above the valve-casing. As is well understood by those skilled in the art, the nitrous oxid and the oxygen are supplied in standard carboys or cylinders which in practice constitute a part of the apparatus and are arranged to supply the bags with gas. In the illustrated embodiment of the invention I make provision for the use of four cylinders, the nitrous-oxid cylinders being indicated by 22 and 23 and the oxygen-cylinders by 24 and 25. These cylinders are grouped around the standard 3 in close proximity thereto, and their discharge-

necks 26 are received within yokes 27, 28, 29, and 30 and retained by set-screws 31, as usual. The several yokes are formed at the outer ends of arms 32, diverging from a hub 33, having a threaded opening 34 for the reception of the threaded upper end of the upper standard-section 4. (See Fig. 3.) The hub 33, the arms 32, and the several yokes are preferably formed in a single casting, which constitutes a yoke-frame located immediately below the pipe connections leading from the nipples 12 and 13 to the inhaler-tube.

Adjacent to each of the nipples 12 and 13 is located a three-way union 35, having connection with a nipple through a short pipe 36, and likewise in communication with the adjacent pair of cylinders through the medium of angularly-disposed pipes or conduits 37 and 38, the remote ends of which are screwed through the proximate sides of a pair of yokes and have their extremities extended into the discharge-necks of the cylinders. The pipes 37 and 38 are equipped with cocks 39 and 40, by means of which either of a pair of cylinders may be placed in communication with a gas-bag to supply the latter with gas. It should be noted at this point that the radial disposition of the arms 32 of the yoke-frame disposes the yokes in angular relation, this being a material feature, since it permits the pipes 37 and 38 to converge at the union 35, arranged in proximity to one of the gas-bag nipples, as already described.

We have now seen that each gas-bag is arranged to be supplied from either of a pair of storage-cylinders and that both bags discharge into a common inhaler-tube through conduits equipped with controlling-valves, whereby the proportion of nitrous oxid and oxygen supplied to the patient may be properly regulated. It also follows from the described arrangement that upon the depletion of one cylinder the gas-bag may be supplied immediately from another cylinder, since it is only necessary for the operator to turn one of the cocks 39 or 40 in order to establish communication between the bag and a new source of supply. This is highly advantageous for the reason that should the supply of nitrous oxid be prematurely exhausted the patient would recover from the anesthesia before another cylinder could be attached in place of the one exhausted. Similarly, if the supply of oxygen should give out the patient would be in danger of asphyxiation before the exhausted cylinder could be replaced by one containing a new supply of oxygen.

As has been premised, one of the primary objects of this invention is to group the entire apparatus in very small compass, so that it may be carried from place to place in a small case and completely set up for instant use when removed from the case and supported thereon or upon a table or the like. It will

be seen by reference to Fig. 1 that all of the parts are arranged compactly over a small base, designed to fit in a case the top of which is located in a plane just above the horizontal pipe. This pipe constitutes a convenient handle, by means of which the apparatus may be lifted from its case and carried about. By exercising reasonable care the cylinders, being secured at their upper ends within the yokes, will remain in their proper positions during the transportation of the apparatus; but in order that their rigid retention in proper position may be absolutely insured I preferably employ what may be termed a "cylinder-retaining frame" 41, comprising a hub 42, vertically adjustable upon the standard 3, and a series of cylinder-receiving rings or sockets 43, having shanks 44 radiating from and screwed into the hub 41. (See Fig. 4.) In order to prevent the turning of the shanks 44, the latter are preferably provided with lock-nuts 45. The cylinder-retaining frame is designed to be held in its adjusted positions by a clamping-screw 46, screwed into the hub and designed to bear against the standard 3. In attaching the cylinders their lower ends are passed into the rings 43, the frame being adjusted in its proper position upon the standard, and the cylinders are clamped within the rings by the clamping-screws 47, one of which is passed through each ring for engagement with the cylinder encircled thereby. The cylinders positioned in the manner described are rigidly secured to the standard by connections at their upper and lower ends, and the entire apparatus, organized for instant use, may therefore be conveniently carried without liability of derangement. A further distinct advantage of the particular organization described resides in the separability of its various parts to facilitate its being packed in still smaller compass—as, for instance, in a suit-case. After removing the cylinder the superstructure grouped upon the upper section of the standard may be detached by unscrewing the upper standard-section from the coupling. The lower section of the standard may then be unscrewed from the socket, the cylinder-retaining frame removed from the standard, and if it is not desired to transport the base the socket may be removed from the latter and subsequently reattached to a table or other support when the apparatus is to be assembled for use. In some instances also I contemplate the attachment of the standard to a suitable folding support or stand, which, however, is not illustrated or specifically described, for the reason that it does not constitute a part of my present invention.

It is thought that from the foregoing the construction, operation, and many advantages of my improved apparatus for administering anesthetics will be apparent with-

out further description; but while the present embodiment of the invention is thought at this time to be preferable I desire to be understood as reserving the right to effect such changes, modifications, and variations of the illustrated structure as may fall fairly within the scope of the protection prayed.

What I claim is—

1. In an apparatus of the character described, the combination with a supporting-
10 stem; of a pair of nipples for the attachment of gas-bags, a third nipple for the attachment of an inhaler-tube, and rigid connections intermediate of the nipples and carried by the
15 stem.

2. In an apparatus of the character described, the combination with a supporting-
20 standard; of a three-way fitting carried thereby, a pair of valve-controlled pipes and a nipple
25 extending in different directions from the fitting, and pendent nipples at the outer ends of said pipes.

3. In an apparatus of the character described, the combination with a standard; of
25 a superstructure carried thereby and including nipples for the attachment of gas-bags, a yoke-frame having cylinder coupling-yokes and valve-controlled pipes leading from the yokes to said nipples, a third nipple for the
30 attachment of an inhaler-tube, and valve-controlled pipes establishing communication between the third nipple and the nipples first named.

4. In an apparatus of the character described, the combination with a supporting-
35 standard, and a nipple disposed at the upper end thereof for the attachment of an inhaler-tube; of valve-controlled pipes in communication with said nipple and rigid with the standard, bag-attaching nipples pendent from the outer ends of said pipes, a yoke-frame carried by the standard and including coupling-yokes designed for attachment to gas-cylinders, and pipes rigid with the yoke-frame
45 and disposed between the yokes and the dependent nipples.

5. In an apparatus of the character described, the combination with a supporting-
50 standard; of a yoke-frame carried thereby adjacent to its upper end, and including a pair of angularly-related yokes designed for attachment to gas-cylinders, a nipple for the attachment of a gas-bag, a pair of angularly-related valve-controlled pipes extending from the angularly-related yokes and communicating with the nipple, and means for leading gas from the nipple to an inhaler.

6. In an apparatus of the character described, the combination with a standard; of
60 a yoke-frame detachably carried thereby adjacent to its upper end and including a pair of angularly-related yokes, a pair of cylinders having their discharge-necks retained in the yokes, a nipple, a gas-bag attached thereto, a

union communicating with the nipple, valve-
65 controlled pipes extending from the union to the yokes, and means for leading gas from the gas-bag to an inhaler-tube.

7. In an apparatus of the character described, the combination with a supporting-
70 standard; of a yoke-frame comprising a hub carried by the standard, radially-disposed arms and yokes located at the outer ends of said arms, a pair of vertically-disposed nipples, valve-controlled pipes establishing communication between each nipple and a pair of yokes, a third nipple for the attachment of the inhaler-tube, and valve-controlled pipes establishing communication between the third nipple and each of the nipples first named.

8. In an apparatus of the character described, the combination with a supporting-
75 standard; of a three-way fitting carried at the upper end thereof, valve-controlled pipes extending in opposite directions from the fitting and having depending nipples at their outer ends, a yoke-frame carried by the standard and comprising a hub and radial arms having terminal yokes for the attachment of cylinders, unions, each having communication with a nipple, angularly-related valve-controlled pipes extending from each union to the adjacent pair of yokes, and means for leading gas from the three-way fitting to an inhaler.

9. In an apparatus of the character described, the combination with a supporting-
90 standard; of a horizontally-disposed yoke-frame carried by the standard adjacent to its upper end, a plurality of cylinders grouped about the standard and having connection with the yoke-frame, vertically-disposed nipples, gas-bags connected thereto, means for establishing communication between said nipples and certain of the cylinders, a third nipple for the attachment of an inhaler-tube, and horizontally-disposed pipe connections carried by the upper end of the standard and establishing communication between the vertically-disposed nipples and the nipple last named.

10. In an apparatus of the character described, the combination with a supporting-
100 standard comprising detachably-connected sections; of a superstructure carried exclusively by the upper section of the standard and comprising a yoke-frame, vertically-disposed nipples for the attachment of gas-bags, valve-controlled pipes extending from the yokes of the frame to the nipple, a third nipple for the attachment of the inhaler-tube, and valve-controlled pipes leading from the said nipple to the nipples first named.

11. In an apparatus of the character described, the combination with a standard; of a cylinder-retaining frame adjustable upon the standard and comprising rings for the reception of the cylinders.

12. In an apparatus of the character described, the combination with a standard; of

a cylinder-retaining frame adjustably mounted thereon and comprising a hub, a series of rings having radially-disposed shanks connected with the hub, means for securing the frame in its adjusted positions, and cylinder-engaging means carried by the rings.

13. In an apparatus of the character described, the combination with a supporting-standard, of a yoke-frame carried thereby and including a pair of yokes designed for attachment to gas-cylinders, a gas-bag, valve-controlled pipes extended from the yokes and communicating with the gas-bag, and means for leading gas from the bag to an inhaler.

14. In an apparatus of the character described, the combination with a supporting-standard, of means for sustaining a pair of gas-bags in proximity to the standard, a plurality of coupling-yokes supported by the standard and adapted to receive a plurality of supply-cylinders for each gas-bag, and valve-controlled pipes for placing each gas-bag in communication with a plurality of yoke-engaged cylinders.

15. In an apparatus of the character described, the combination with a supporting-standard, of a yoke-frame carried thereby and including a pair of yokes designed for attachment to gas-cylinders, a nipple for the attachment of a gas-bag, pipes extending from the yokes and communicating with the nipple, and means for leading the gas from the nipple to an inhaler.

16. In an apparatus of the character described, the combination with a supporting-standard, of a yoke-frame carried thereby and including a plurality of yokes designed for attachment to gas-cylinders, a pair of nipples for the attachment of gas-bags, a third nipple for the attachment of an inhaler-tube, and pipe connections intermediate of the nipples and carried by the standard.

17. In an apparatus of the character described, the combination with a supporting-standard, of a plurality of gas-bags, a yoke-frame carried by the upper end of said standard and including a plurality of rigidly-connected yokes, cylinders connected to the yokes, means for placing one of the gas-bags in communication with either of a plurality of said cylinders, means for placing the other gas-bag in communication with a cylinder, and means for supplying an inhaler with gas from both bags.

18. The combination with a supporting-standard, and a yoke-frame adjustably mounted thereon and including two pairs of connected yokes, cylinders suspended from said yokes, a pair of gas-bags, an inhaler, supporting means for said bags carried by the standard and including pipe connections for establishing communication between the gas-bags and the inhaler, and means for placing each

bag in communication with either one of a pair of cylinders.

19. In an apparatus of the character described, the combination with a base provided with a socket, of a supporting-standard detachably received by the socket and comprising detachably-connected upper and lower sections, gas cylinders and bags, and means carried by the upper section of the standard for establishing communication between the cylinders and bags and for leading gas from the bags to an inhaler.

20. In an apparatus of the character described, the combination with a supporting-standard, of a yoke-frame carried thereby and including a series of rigidly-connected coupling-yokes for the upper ends of gas-cylinders, a cylinder-retaining frame adjustably mounted on the standard below the yoke-frame and comprising means for the reception of the cylinders, nipples for the attachment of gas-bags, pipes leading from said nipples to the yokes of the yoke frame, and means for leading gas from the nipples to an inhaler.

21. In an apparatus of the character described, the combination with a pair of gas-bags and a flexible inhaler-tube, of a rigid structure including cylinder-coupling yokes adapted to engage the discharge-necks of gas-cylinders, and rigid valve-controlled metal connections for establishing communication between the cylinders and bags and between the bags and the inhaler-tube.

22. In an apparatus of the character described, the combination with a plurality of gas-bags, a supporting-standard and cylinder-coupling yokes rigid with the standard, of gas-cylinders connected to said yokes, a flexible inhaler-tube, and valve-controlled metal connections rigid with the supporting-standard and arranged to establish connection between the cylinders and bags and between the bags and the inhaler-tube.

23. In an apparatus for administering anesthetics, the combination with a supporting-standard and a plurality of cylinders and a bag grouped about the standard; of a rigid superstructure carried by the standard at the upper extremity thereof and constituting a support for the cylinders and bag, said rigid superstructure including the following elements, to wit, cylinder-coupling yokes adapted to engage the discharge-necks of gas-cylinders, valve-controlled conduits for leading gas from the cylinders to the bag, and a nipple for the attachment of an inhaler-tube.

In testimony that I claim the foregoing as my own I have hereto affixed my signature in the presence of two witnesses.

RAYMOND C. COBURN.
